UNITED STATES PATENT OFFICE

HUGH K. CHRISTIE, OF HARVEY, ILLINOIS, ASSIGNOR TO WHITING CORPORATION, OF HARVEY, ILLINOIS, A CORPORATION OF ILLINOIS

DROP PIT JACK

Application filed March 1, 1930. Serial No. 432,361.

The invention relates to drop-pit jacks.

The objects of the invention are to provide; a single-screw jack which is adapted more particularly for lighter work in repair shops, such as the removal of the tender-wheels, car-axles, and the like; a single-screw jack with simple mechanism, including an electric motor for operating the screw; a screw jack of this type which is adapted to operate in a comparatively shallow pit; and a single-screw jack in which the lower end of the lifting screw is efficiently protected against the entry of water which sometimes accumulates in the bottom of the pit, and is guided to prevent cramping of the screw. Other objects of the invention will be apparent from a consideration of the following detailed description.

The invention consists in the several novel features hereinafter set forth and more particularly defined by claims at the conclusion hereof.

In the drawings: Fig. 1 is a transverse section of a screw jack and pit embodying the invention. Fig. 2 is a transverse section. Fig. 3 is a plan of the truck, the top of the gear-case and the platform being removed. Fig. 4 is a section on line 4—4 of Fig. 2.

The jack which forms the subject matter of the invention is mounted on a wheeled truck in a pit and is adapted for use in connection with a shop having a track which extends over the pit and permits railway rolling stock needing wheel or axle repair to be brought into position over the jack, so that the axles and wheels to be repaired may be removed by the jack. The pit, as illustrated in the drawings, extends crosswise of the track on the shop floor and is below the track level. The track on the floor comprises fixed rail sections a laid in the floor a^3 of the shop and on sleepers a' and pit-bridging sections a^2 which are pivotally supported as they may be swung into bridging position or transversely thereto to clear the pit so an axle with its wheels can be lowered. Each of the rail-sections a^2 is fixed on a beam a^4 which is pivotally mounted on a vertical bracket a^5 , being connected thereto by a vertical pivot-rod a^6 which extends vertically

through lugs at the top and bottom of said bracket. A brace-rod a^7 extends between the lower end of the pivot rod a^6 and the central portion of the beam a^4 , and a brace-rod a^8 extends between the central portion of brace a^7 and the upper end of the rod a^6 . Stop plates a^9 and a^{10} are secured to the rail-sections a^2 and rails a respectively to align the said sections and rails. This construction permits each of the rail-sections a^2 to be swung into position to bridge the rails a or transversely thereto to clear the pit below the track. A work-pit b in the floor extends longitudinally of the track, so that workmen can inspect or work on parts underneath the rolling stock. The transfer pit c intersects the working pit b , and is provided with rails c' laid on sleepers c^2 which are secured on the bottom wall c^3 of the pit c , and these rails form a track for wheeled truck D which carries the screw-jack for raising and lowering the axle wheels.

The truck D comprises a frame composed of longitudinal channelled side-beams d and channelled cross-beams d' at the ends of, and rigidly secured to, the side-beams by plates d^2 . Carrying wheels d^3 are adapted to run on the rails c' and are secured to axles d^4 which are mounted in bearings d^5 fixed to the side beams d . These wheels are disposed inwardly of the side beams. A platform d^6 , preferably of wood, is laid and secured on strips d^7 , so that the workmen may conveniently walk on the truck and across the transverse pit, and so that parts may be laid thereon and transported along the pit.

A pair of transverse channel beams e are secured by angle plates e' to the side beams d of the truck-frame to support the lifting-screw and its operating gearing. The lifting mechanism comprises a single, vertical, bodily movable screw g , the upper end of which is provided with a fork or bracket g' for engaging an axle. The lower end of the screw is fixed by a pin g^2 to a collar or head g^3 , which is held against rotation to secure the screw against rotation. A gear housing, composed of upper and lower sections f and f' , bears on the top flanges of, extends between, and is fixed to, the beams e , and the

load stresses are transmitted to the truck through said casing and onto said beams *e*. A worm-gear *h* has fixed thereto a hub or sleeve *h'* which is threaded to the screw *g*, 5 and which, by rotation relatively to the screw, will raise or lower the screw to correspondingly shift the load on the bracket *g'*. An anti-friction thrust-bearing *h²* is interposed between the gear *h* and the lower section *f'* of the gear-housing. The screw *g* extends loosely through the housing section *f'* so it is free to move bodily and vertically through the gear housing. Hub *h'* is journalled in upper housing section *f*, shouldered 15 to bear against said section so it will be held against upward movement, and the gear *h* is free to rotate, but held against vertical movement in the gear-housing. A circular flange *f²* extends into a groove in the upper face of gear *h* to prevent cramping stresses 20 between the sleeve *h'* and its bearing in the upper housing section.

A housing for the collar *g³* is suspended from the beams *e*, and comprises end plates *h* having their outer faces fitting against the inner faces of beams *e*, a bottom wall *h²* secured to walls *h* by angle irons *h³*, and side walls *h⁴*. The upper ends of the end walls *h* are extended laterally, and angle bars *h⁵*, secured to said walls, are secured to the bottom flanges of the beams *e*. The lower portion of the housing *h* is of reduced width, and a channel *c⁴* is formed in the bottom of the pit *c* to permit the housing to travel lengthwise of the pit and transversely to the track on the floor of the shop. Vertical guide-bars *h⁶* are secured to the inner sides of the end walls *h*, and the collar or head *g³*, which is fixed to the lower end 40 of the screw is formed with channels *g³⁰*, to receive the guides so the collar will be slideable vertically with the screw *g*, but will be held against rotation, so that when the gear *h* is rotated, the screw will be bodily raised 45 or lowered. Besides holding the screw against rotation, the head *g³* will be guided to vertically and truly hold the lower end of the screw, to prevent cramping between the screw and the sleeve *h'* or between the 50 sleeve and the gear-housing. Additionally, the housing for the head *g³*, besides sustaining the guides *h⁶*, prevents water from reaching the screw and head in event that any water accumulates in the channel *c⁴* or the 55 pit *c*.

Power mechanism, for rotating the gear *h* to raise and lower the screw, comprises a reversible electric motor *m* which is mounted on angular cross bars *m'* which extend under 60 and are secured to the bottom flange of the side beams *d*; a pinion *m²* on the shaft of the motor, a silent drive-chain *m³* driven by said pinion, a sprocket *m⁴* driven by said chain and fixed to one end of a transverse shaft *m⁵* 65 which extends across one end of, and is jour-

nalled in the gear-housing *f*, *f'*, and a worm *m⁶* fixed to shaft *m⁵* and meshing with gear *h*. A gear cover *m⁷* is secured to the platform *d⁶* and extends over the sprocket *m⁴*. This construction exemplifies a wheeled 70 transfer truck provided with a single screw for raising and lowering the load in the pit, and gearing operated by a motor on the truck for raising and lowering the screw.

In operation, the motor *m* will be controlled to rotate gear *h* in either direction according to whether the screw *g* is to be raised or lowered. During this operation, the head *g³*, fixed to the lower end of the screw, will hold the screw against rotation and guide it vertically. When the screw *g* has been lowered, the bracket *g'* at the upper end thereof will be disposed in pit *c* and low enough to permit it to pass under the bridging rail-sections *a*, and the beams *a⁴* on which they are supported, while the car or tender is on the track and over the pit. The motor, which is of the reversible type, will then be operated to rotate the gear *h* in one direction so the screw *g* will be raised, until its bracket *g'* has engaged the axle and lifted it from the rail-sections *a²*. When the axle has been disconnected from the car or tender and lifted to clear the rails, the rail-sections *a²* 95 will be swung laterally to clear the pit so the axle and wheels can be lowered. Next, the motor *m* will be operated to lower the screw to lower the axle and wheels into the pit, so that they can be transported transversely of the car track and longitudinally of the pit while on the truck *D*, to another intersecting track or any place where the axles and wheels are to be worked on or removed.

The invention exemplifies a drop pit provided with lifting mechanism, which comprises a single screw for raising and lowering the load which is mounted on a wheeled truck to travel longitudinally of the pit; which is mounted on the truck for raising and lowering the screw; in which the gearing for operating the screw is enclosed in a case which is adapted to retain lubricant to keep the screw and working parts well lubricated; in which a housing for the lower end of the screw and its head extends under the truck and into the channel in the pit to prevent water from reaching the screw and its head, and to guide the lower end of the head vertically; which is simple in construction, and can be produced at a low cost.

The invention is not to be understood as restricted to the details set forth, since these may be modified within the scope of the appended claims, without departing from the spirit and scope of the invention.

Having thus described the invention, what I claim as new and desire to secure by Letters Patent is:

1. In apparatus of the character described, 130

the combination of a floor track, a pit intersecting the track, a wheeled truck movable to traverse the pit crosswise of the track, a single vertically movable lifting-screw mounted on and centrally of the truck and provided with means at its upper end for receiving a load, gearing on the truck for raising and lowering the screw, a motor stationarily mounted on the truck and connected to operate said gearing, and means at the lower end of the screw for holding it against rotation.

2. In apparatus of the character described, the combination of a floor track, a pit intersecting the track, a wheeled truck movable to traverse the pit crosswise of the track, a single vertically movable lifting screw mounted on and centrally of the truck and provided with means at its upper end for receiving a load, gearing on the truck for raising and lowering the screw comprising a worm gear on the screw and a worm engaging said gear, an electric motor mounted on the truck and connected to operate said gearing, and means for holding the screw against rotation.

3. In apparatus of the character described, the combination of a floor track, a pit intersecting the track, a wheeled truck movable to traverse the pit and crosswise of the track, a single vertically movable lifting screw mounted on and centrally of the truck and provided with means at its upper end for engaging a load, gearing on the truck for raising and lowering the screw, an electric motor stationarily mounted on the truck connected to operate said gearing, a head on the lower end of the screw, and a housing depending from the truck and in which the head travels.

4. In apparatus of the character described, the combination of a floor track, a pit intersecting the track, a wheeled truck movable to traverse the pit crosswise of the track, a single vertically movable lifting screw mounted on and centrally of the truck and provided with means at its upper end for engaging a load, gearing on the truck for raising and lowering the screw, an electric motor stationarily mounted on the truck and connected to operate said gearing, and slidably mounted means depending from the truck for guiding the lower end of the screw.

5. In apparatus of the character described, the combination of a floor track, a pit intersecting the track, a wheeled truck movable to traverse the pit crosswise of the track, a single vertically movable lifting screw mounted on and centrally of the truck and provided with means at its upper end for engaging a load, gearing on the truck for raising and lowering the screw, an electric motor stationarily mounted on the truck and connected to operate said gearing, and a housing depending from the truck and provided with

a vertical guide for holding the screw against rotation.

6. In apparatus of the character described, the combination of a floor track, a pit intersecting the track, a wheeled truck movable to traverse the pit crosswise of the track, a single vertically movable lifting screw mounted on and centrally of the truck and provided with means at its upper end for engaging a load, gearing on the truck for raising and lowering the screw, a motor stationarily mounted on the truck and connected to operate said gearing, and means depending from the truck for guiding the lower end of the screw and holding it against rotation.

7. In apparatus of the character described, the combination of a floor track, a pit intersecting the track, a wheeled truck movable to traverse the pit crosswise of the track, a single vertically movable lifting screw mounted on and centrally of the truck and provided with means at its upper end for engaging a load, gearing on the truck for raising and lowering the screw, an electric motor mounted on the truck and connected to operate said gearing, a head on the lower end of the screw, a rigid housing depending from the truck, and vertical guides in the housing interfitting said head.

8. In apparatus of the character described, the combination of a floor track, a pit intersecting the track, a wheeled truck movable to traverse the pit crosswise of the track, a single vertically movable non-rotatable lifting screw mounted on and centrally of the truck and provided with means at its upper end for engaging a load, transverse beams on the truck, a gear-case mounted on the beams, gearing in said case, for raising and lowering said screw, and an electric motor mounted on the truck and connected to operate said gearing.

9. In apparatus of the character described, the combination of a floor track, a pit intersecting the track, a wheeled truck movable to traverse the pit crosswise of the track, a single vertically movable non-rotatable lifting screw mounted on and centrally of the truck and provided with means at its upper end for engaging a load, transverse beams on the truck, a gear case mounted on the beams, gearing in said case for raising and lowering said screw, an electric motor mounted on the truck and connected to operate said gearing, and a housing depending from said beams in which the lower end of the screw travels.

10. In apparatus of the character described, the combination of a floor track, a pit intersecting the track, a wheeled truck to traverse the pit crosswise of the track, a single vertically movable lifting screw mounted on and centrally of the truck and provided with means at its upper end for engaging a load, spaced transverse beams on

the truck, a gear-case mounted on the top of and extending between the beams, gearing in said case for raising and lowering said screw, and an electric motor mounted on the truck and connected to operate said gearing.

5 11. In apparatus of the character described, the combination of a floor track, a pit intersecting the track, a wheeled truck to traverse the pit crosswise of the track and comprising a frame with side-beams and end-beams rigidly secured together, wheels disposed inwardly of the side beams, a single vertically movable lifting screw carried by the truck, a pair of transverse beams secured to the side beams of the truck-frame, gearing for raising and lowering the screw, a gear-support mounted on said pair of transverse beams, means for vertically guiding the lower end of the screw, and an electric motor mounted on the truck, connected to operate said gearing.

10 12. In apparatus of the character described, the combination of a floor track, a pit intersecting the track, a wheeled truck to traverse the pit crosswise of the track and comprising a frame with side-beams and end-beams rigidly secured together, wheels disposed inwardly of the side beams, a single vertically movable lifting screw carried by the truck, a pair of transverse beams secured to the side beams of the truck-frame, gearing for raising and lowering the screw, a gear-support mounted on said pair of transverse beams, a vertical guide for the lower end of 15 the screw, a housing depending from the transverse beams containing the guide, and an electric motor mounted on the truck and connected to operate said gearing.

13. In apparatus of the character described, the combination of a floor track, a pit intersecting the track, a truck to traverse the pit crosswise of the track and comprising a frame with side-beams and end-beams rigidly secured together, wheels disposed inwardly of the side beams, a single vertically movable non-rotatable lifting-screw carried by the truck, gearing for raising and lowering the screw, a gear support on the frame, a platform over said frame, and an electric motor mounted on the truck under the platform and connected to operate said gearing.

Signed at Harvey, Illinois, this 24th day of February, 1930.

55 HUGH K. CHRISTIE.
